COMBINED HAT RACK AND CONTROL PANEL UNITS FOR AN AIRCRAFT

Frank A. Ilenin, Bloomfield Hills, and Paul J. Petlewski, Detroit, Mich., Marlan H. Polhemus, Chicago, Ill., and Gordon W. Severson, Detroit, and Robert G. Plantholt, Drayton Plains, Mich., assignors to General Dynamics Corporation, San Diego, Calif., a corporation of Delaware

Application December 15, 1958, Serial No. 53,772

Term of patent 14 years

(Cl. D71—1)

Figure 1 is a perspective view showing the front and one end of a combined hat rack and control panel units for an aircraft embodying our new design;

Figure 2 is a transverse sectional view thereof taken between control panel units of the combination;

Figure 3 is a perspective view on an enlarged scale of one of the control panel units; and

Figure 4 is a side elevational view of a control panel unit as shown in Figure 3.

The end not shown is a mirror image of that shown in Figure 1 and the rear is substantially plain.

We claim:

The ornamental design for a combined hat rack and control panel units for an aircraft, substantially as shown and described.
